UNITED STATES PATENT OFFICE.

AUGUSTUS F. NAGLE, OF MONTCLAIR, NEW JERSEY, ASSIGNOR TO EARLE H. GOWING, OF READING, MASSACHUSETTS.

MECHANICAL STOKER.

SPECIFICATION forming part of Letters Patent No. 703,450, dated July 1, 1902.

Application filed July 6, 1901. Serial No. 67,343. (No model.)

To all whom it may concern:

Be it known that I, AUGUSTUS F. NAGLE, of Montclair, in the county of Essex and State of New Jersey, have invented certain new and useful Improvements in Mechanical Stokers, of which the following is a specification.

My invention relates especially to furnaces having an inclined bottom and to stokers therefor in which the screw conveyer supplies coal continuously to the rear end of the furnace and deposits it upon the upper portion of the inclined bottom, down which it is carried by gravity and by the impelling force of the screw. These inclined bottom plates are corrugated longitudinally, made independently removable, and are separated by raised twyers, which supply blasts of hot air projected laterally downward from vents in the upper part of each lateral face. I provide a plurality of screw conveyers, each discharging down the incline at the rear of the furnace between adjacent rows of twyers in the direction toward the furnace-door. These conveyers may lead direct from a hopper beyond the rear wall; but under a special feature of my invention the main conveyer rises obliquely beneath the furnace-bottom from the hopper in front to a transfer-chamber in the rear, where another screw, geared to the shaft of the main screw, reverses the direction of movement of the coal and discharges it into the furnace. At the foot of the incline there are horizontal bottom plates, on which also combustion occurs, and ashes gather to be removed through the front door on a level therewith. An opening is formed through the front wall at a higher level and provided with a transparent or other door to afford a view of the interior of the furnace.

In the drawings, Figure 1 is a longitudinal vertical section through a furnace and stoking apparatus embodying my invention. Fig. 2 is a transverse vertical section thereof on line 2 2 of Fig. 1. Fig. 3 is a vertical section showing the hopper at rear of the furnace. Figs. 4, 5, and 6 are details of the reversing conveyer, and Fig. 7 an enlarged cross-section of the peculiar twyer and floor-supports on line 7 7 of Fig. 1.

A represents the front wall, B the rear wall, and C the side walls, of the furnace.

D is the boiler, suitably mounted over the fire- or combustion chamber E, F the ash-door, and G an opening in the front wall for inspection of the interior of chamber E. 55

The floor I of the combustion-chamber at the front is horizontal and about level with the door F; but the rear portion H inclines quite sharply upward therefrom and is formed of a series of corrugated metal plates, each 60 resting marginally upon the oblique portion of the inclined and horizontal beams J, supported by the front and rear walls A B, Fig. 1. The plates H and I are separately removable, so that a new one can at any time be 65 substituted. There may be a horizontal ledge or plate at the rear of the inclined floor, as indicated in Fig. 1; but this is not essential.

Between adjacent plates H are rows of hollow twyers K, supported on the beams J and 70 suitably secured in position, preferably by bolts L, having enlarged heads within each twyer and keyed fast underneath. At all other points there is open space between the beams, admitting air under pressure from 75 beneath into the twyers and thence into the combustion-chamber through downwardly-extending vents k in each lateral face.

The fuel from hopper M is introduced through the rear wall B, at top of the inclined 80 bottom H, by means of a screw conveyer suitably actuated. In Fig. 3 the hopper is located at the rear, the conveyer-tube N and screw O run direct therefrom to the furnace, and the coal is discharged upon the upper 85 end of the incline, as stated. In the apparatus shown in Figs. 1 and 2 the hopper is in front, the main conveyer P Q rises obliquely from it, beneath the furnace-bottom, to a transfer-chamber R in the rear wall. From 90 this chamber a return-tube S extends to the furnace at top of the incline and incloses a short reversing conveyer-screw T. The shafts of screws Q and T are connected by suitable gearing U, and when motion is imparted to 95 screw Q the coal brought into chamber R is discharged by screw T into the furnace at top of the inclined floor.

By reference to Figs. 1 and 2 it will be seen that each return-tube S and its inclosed screw 100 T is in position to discharge the fuel upon the corrugated inclined plate H, between the

rows of twyers K, where combustion will take place as the fuel gradually works downwardly to the lowest floor-level. The mechanism will be driven by a suitable motor, as V, Fig. 1.

5 I claim as my invention—

1. The combination with a furnace having a downwardly-inclined combustion-surface and an ash-door opposite the lower end thereof, said combustion-surface being constructed to retain the unconsumed material for removal through said door, of a furnace-stoking apparatus adapted to supply fuel to the combustion-chamber through the rear wall thereof and to project such fuel upon said inclined surface.

15 2. The combination with a furnace having in its rear portion forwardly-inclined combustion-plates and a door opposite the lower end thereof, the entire floor of the combus-

tion-chamber being constructed to retain unconsumed material for removal through said door, of a conveying-screw and tube opening through the rear wall above said plates and coöperating with gravitation to carry fuel toward said door.

20 3. The combination with a furnace having forwardly-inclined combustion-plates and interposed elevated twyers, of a plurality of screw conveyers introducing fuel through the rear wall and depositing it on said inclined plates between adjacent rows of twyers.

25 In testimony whereof I have affixed my signature in presence of two witnesses.

AUGUSTUS F. NAGLE.
